UNITED STATES PATENT OFFICE.

FRANK HORNQUIST, OF KANE, PENNSYLVANIA, ASSIGNOR TO THE SAFETY SLED COMPANY, OF MOUNT JEWETT, PENNSYLVANIA.

SLED.

1,036,245.

Specification of Letters Patent. Patented Aug. 20, 1912.

Application filed October 26, 1911. Serial No. 656,868.

To all whom it may concern:

Be it known that I, FRANK HORNQUIST, a citizen of the United States, residing at Kane, in the county of McKean and State of Pennsylvania, have invented certain new and useful Improvements in Sleds; and I do declare the following to be a full, clear, and exact description of the invention, such as will enable others skilled in the art to 10 which it appertains to make and use the same.

This invention relates to improvements in sleds.

The main object of the invention is to provide a sled having a combined one-piece cross beam and runner support which is very light, strong, and durable.

Another object is to provide an improved construction of jointed runner, whereby a 20 smooth surface engaging face is produced.

A further object is to provide improved swinging foot rests which will swing automatically into inoperative position when the sled is going up a hill.

25 Another object is to provide simple and efficient holding means for locking the jointed runners in rigid position.

With these and other objects in view the invention consists of certain novel features 30 of construction, combination and arrangement of parts as will be more fully described and particularly pointed out in the appended claim.

In the accompanying drawings: Figure 1 35 is a top plan view of a sled constructed in accordance with this invention, showing in dotted lines the manner in which the sled is steered; Fig. 2 is a bottom plan view thereof; Fig. 3 is a central vertical longitudinal 40 sectional view; Fig. 4 is a perspective view of the blank from which the combined runner support and cross beam is formed; Fig. 5 is a transverse vertical section taken on the line 5—5 of Fig. 1; Fig. 6 is an enlarged 45 horizontal sectional view of a portion of one of the runners, showing the construction of the improved joint; Fig. 7 is a side elevation of the joint; Fig. 8 is an enlarged detail sectional view showing the locking 50 means for holding the runners rigidly con-

nected to the seat or body portion of the sled; Fig. 9 is a detail perspective view of one of the stirrups. Fig. 10 is a detail side elevation of a runner showing another form of joint; Fig. 11 is a bottom plan view 55 thereof.

In the embodiment illustrated, a sled top or seat 1 is shown in the form of a series of slats secured to the cross bars 2, the ends of which are fastened to longitudinal side bars 60 3 and the forward ends of these side bars are riveted or otherwise secured to a front cross bar 4.

The cross bars or beams 2 are preferably constructed from a single piece of sheet 65 metal in the form shown in Fig. 4, consisting of a body portion 5 having diverging laterally extending arms 6 and 7 on its opposite sides near its opposite ends, and with extensions 8 and 9 formed at the ends between 70 said arms. These extensions are offset from the body portion to form members for engagement with the lower faces of the side bars 3, as is clearly shown in Fig. 2. The body portion of this beam has its side 75 edges bent to form parallel substantially right angular flanges 10 and 11, whereby the beam is greatly strengthened. The arms 6 and 7 are preferably bifurcated at their free ends, as shown in Fig. 4 and are folded longitudinally throughout the greater portion of their length and said bifurcated ends engaged with opposite faces of the runner ribs hereinafter described. These arms are first bent substantially at right angles to the 85 body portion 5 of the beam and are then folded longitudinally to form reinforced runner supports, the bifurcated ends of which are riveted or otherwise suitably secured to the runners. The slats of the seat 80 portion of the sled are riveted to the body portion of these beams and this peculiar formation of the beams renders them light, strong, and durable as well as inexpensive to manufacture.

95 The runners 12 are here shown as constructed of angle iron and are T-shaped in cross section, as shown in Fig. 5 with their lower faces rounded to form smooth surface engaging faces. These runners have one or 100

more joints as 13 formed therein one of which is shown in the present instance. This joint 13 is shown located adjacent to the front support formed by the arms of 5 the front cross bar 2, and said joint is formed as shown in Figs. 10 and 11 by providing the inner end of the tread portion of the front section with a curved recess 14 and the adjacent end of the rear section with a 10 curved rounded projection 15. The webs or ribs of the runner sections are preferably connected by hinge members 16 and 17 secured to the adjacent ends and pivotally connected by a pintle 18 which engages the 15 knuckles of the hinge members 16 and 17 and thereby hingedly connects the runner sections. By this connection, a smooth, flat, unobstructed surface will be provided on the lower face thereof to provide for the 20 smooth running of the sled without jarring or jolting. In Figs. 10 and 11 a slightly different form of joint is shown in which the adjacent ends of the sections are provided with overlapping longitudinal extensions 12^a and 12^b the inner or upper face of the extension 12^a on the front section being beveled toward its free end to form a knife edge which is rounded or curved on the arc of a circle to fit in a correspondingly curved 25 recess 12^c formed at the base of the extension 12^b on its lower or outer face. The outer face of this extension 12^b is beveled toward its free end and laps under the extension 12^a as shown in Fig. 10. This close 30 fitting joint forms a smooth unbroken surface and no foreign matter can enter between the sections. The forward ends of these runners are curved upwardly in the usual manner and the free ends thereof are 35 riveted or otherwise secured to a cross bar 19 which has a laterally sliding engagement with the front cross bar 4 to which the side bars of the body or seat portion of the sled are attached. This bar 19 is preferably 40 notched, as shown at 20 to receive a locking hook member 21 pivotally mounted on one of the side bars 3, the hooked end thereof being designed to pass through a notch 4' in the front cross bar 4 and to engage the 45 notch 20 in the cross bar 19 when the runner sections are arranged in a longitudinal alinement, and which thereby locks said sections rigidly together and prevents any lateral movement thereof relative to each other. 50 The central slat of the top or seat of the sled extends beyond the forward ends of the side slats and is pivotally connected to the inner end of a connecting bar 22, the outer end of which is pivotally connected to the 55 lower front cross bar 19. The end of said connecting bar 22 is offset adjacent to its point of connection with the cross bar 19. A transversely arranged steering bar 23 is connected intermediately of its ends to the

connecting bar 22 near the front end of the sled and the opposite ends of said steering bar project over and beyond the side bars 3 of the sled. The steering bar 23 is braced by a short connecting bar 24 rigidly secured at its front end to the upper side of 65 the steering bar and at its rear end is pivotally connected to the front end of the central slat of the sled seat. By thus rigidly connecting the steering bar 23 to the connecting bar 22 and pivotally connecting the latter to the seat of the sled and to the cross bar of the jointed sections of the runners, it will be obvious that by pressing one end or the other of the steering bar either by the hands or by the feet, that the front pivoted sections of the runners may be readily turned in either direction, thereby steering 70 the sled. 75

The foot rests 25 and 26 are pivotally connected with the lower faces of the side bars 80 3 at any suitable or desired point thereon and any desired number of these rests may be used according to the number of persons the sled is designed to carry. These foot rests are preferably constructed as shown in 85 detail in Fig. 9 being formed of strips of metal pivotally connected to the side bars near one end with their other ends extending beyond the side bars of the sled and twisted to form foot receiving stirrups 27. 90 The free connecting ends of these members are bent upwardly at right angles to form stops for engaging the inner faces of the side members 3 for limiting the movement of said rests when swung in opposite directions, the stirrups 27 being heavier than the inner ends of these rests, will swing inwardly and owing to their curvature the free ends thereof will extend under the side bars of the sled when the front end of the 95 sled is turned upwardly in the position which it assumes when going up a hill, and thereby all danger of said stirrups engaging and tearing the clothes is avoided.

From the foregoing description taken in 100 connection with the accompanying drawings, the construction and operation of the invention will be readily understood without requiring a more extended explanation.

Various changes in the form, proportion 115 and the minor details of construction may be resorted to without departing from the principle or sacrificing any of the advantages of this invention as defined and claimed.

I claim as my invention:

A combined cross beam and runner support for sleds composed of a single piece of metal having arms on both sides thereof, the ends of which arms are bifurcated, the latter being folded longitudinally from said 125 bifurcated ends within a suitable distance from the flat body portion of the beam, the

ends of said body portion being provided with extensions beyond the arms and bent to receive and support the side bars of the sled, the bifurcated ends of the arms thus formed being adapted for attachment to the runners of the sled.

5 In testimony whereof I have hereunto set

my hand in presence of two subscribing witnesses.

FRANK HORNQUIST.
